FLUID-COMPRESSOR.

1,326,027.

Specification of Letters Patent. Patented Dec. 26, 1919.

Application filed March 14, 1918. Serial No. 222,504.

To all whom it may concern:

Be it known that I, GEORGES CLAUDE, a citizen of the French Republic, residing at 48 Rue St. Lazare, Paris, in the Republic of France, have invented certain new and useful Improvements in Fluid-Compressors, of which the following is a specification.

The present invention relates to two-stage gas-compressors of the vertical type, which are actuated directly, without the interposition of a shaft, by a steam or other expansion engine. It is known that in engines so constituted it is advantageous, in order to improve the mechanical efficiency, to mount in alinement on the same rod the piston or pistons of the engine and the piston or pistons of the compressor. It has also been suggested, still with the same object in view, to make these pistons of considerable weight, with a view to eliminating the part played by the fly-wheel. But under these circumstances, the engine being vertical, the comparatively great weight of the pistons acts as a resisting effort during their up stroke and as a driving effort during their down stroke. This fact has the disadvantage that the work is not equal during the two strokes, which is prejudicial to the efficiency.

To remedy this, in accordance with the present invention the action of the atmospheric pressure on the compressor piston is utilized. The accompanying diagrammatic drawing, given by way of example, will enable it to be understood how this may be carried out. AB is the two-stage compressor cylinder, the upper side A constituting the first stage and the lower side B, the volume of which is diminished by a portion of reduced diameter serving as a guiding sheath for a reduced portion of the compressor piston constituting the second stage.

This reduced portion of the compressor cylinder is open to the atmosphere at its lower end. The steam cylinder C surmounts the compressor, and the two pistons, of which the compressor piston is comparatively heavy, are connected to one another by a common piston rod.

It will be seen that by this arrangement the compressor piston is constantly subjected at its lower part to the pressure of the atmosphere, which acts upwardly on a cross-sectional area equal to that of the guiding sheath. It will be understood that it is easy to calculate the dimensions of the engine in order that this thrust may be practically equal to the weight of the pistons and piston rod as a whole, which it in this way balances.

What I claim is:

The combination of a two stage vertical compressor comprising a cylinder having one portion of less diameter than the other, said portion of less diameter being open at its lower end to the atmosphere, a piston of considerable weight working within the portion of larger diameter, and having a reduced portion entering into and guided by the portion of the cylinder of less diameter, and an engine working expansively located above said compressor and comprising one or several cylinders, one or several pistons of considerable weight working therein, the piston of said compressor and said second mentioned piston being mounted upon and connected by a single rod, the weight and dimensions of the parts being so calculated that the pressure of the atmosphere acting upwardly on the portion of the compressor piston of reduced diameter is substantially equal to the weight of the pistons and their connecting rod which it balances.

GEORGES CLAUDE.
